CLAIM

The ornamental design for an agricultural machine, as shown and described.

DESCRIPTION

The patent or application file contains at least one drawing executed in color. Copies of this patent or patent application publication with color drawing(s) will be provided by the Office upon request and payment of the necessary fee.

Fig. 1.1 is a perspective view of an agricultural machine showing our new design;

Fig. 1.2 is a rear elevation view thereof;

Fig. 1.3 is a front elevation view thereof;

Fig. 1.4 is a left-side view thereof;

Fig. 1.5 is a right-side view thereof;

Fig. 1.6 is a top plan view thereof;

Fig. 1.7 is a bottom plan view thereof;

Fig. 2.1 is a perspective view of an agricultural machine showing another embodiment of our new design;

Fig. 2.2 is a rear elevation view thereof;

Fig. 2.3 is a front elevation view thereof;

Fig. 2.4 is a left-side view thereof;

Fig. 2.5 is a right-side view thereof;

Fig. 2.6 is a top plan view thereof; and

Fig. 2.7 is a bottom plan view thereof.

The portions of FIGS. 1.1., 1.6, 1.7, 2.1, 2.6 and 2.7 covered by a green overlay show portions of the agricultural machine that form no part of the claimed design.
